UNITED STATES PATENT OFFICE

2,545,082

ELECTRONIC SWITCHING DEVICE

Igor E. Grosdoff, Princeton, N. J., assignor to
 Radio Corporation of America, a corporation
 of Delaware

Application May 28, 1946, Serial No. 672,748

1 Claim. (Cl. 250—27)

1 This invention relates to electronic switching devices. More particularly it provides an improved switching device and method of operation whereby an electrical circuit may be opened or closed within a time interval which is of the order of one hundred millionth of a second (10^{-8} sec.). The invention is illustrated herein as utilized to control the admission of high frequency pulses to a counter by which the number of admitted pulses is indicated. It has utility in various other cases where high speed switching operations are involved.

When utilized to control the admission of high frequency pulses to a counter, the improved switching device of the present invention may be regarded as a mixer of two unrelated signals, one signal being the pulses to be counted and the other signal being the start and stop pulses defining the interval during which the count is to take place. Under these conditions, the pulses to be counted are passed through a gate which is opened and closed in response to the start and stop pulses. This gate may be in the form of a space discharge device such as a triode which is made conductive by the start pulse and is made non-conductive by the stop pulse.

In order that the counting of the pulses be accurately timed, it is essential (1) that the opening and closing times of the gate be shorter than the period of the counted pulses and (2) that the counter be unaffected by the switching pulses. As the frequency of the counted pulses increases and as the time of the count decreases, the necessity of rapid opening and closing of the gate increases. In accordance with the present invention, such rapid opening and closing of the gate is effected by means of electron discharge devices of the gaseous conduction type which are substantially instantaneous in their response to the timing or start and stop pulses.

Heretofore a square wave representing the time of the count has been produced by trigger circuits of the multivibrator type. It is well known that the time required for such a trigger circuit to change from one of its stable conditions to the other is finite and that the square wave which it produces has different slopes at its opposite ends. This is especially notable at the end of the wave where a free discharge is taking place for the reason that the sharpness of the wave front at this point depends on the RC constant of the discharge circuit. Such time lag in the operation of the gate and such difference in the slope at the opposite ends of the timing wave are likely to result in the skipping

of pulses that should be indicated by the counter.

In accordance with the present invention, this difficulty is avoided by the provision of a space discharge device or triode which (1) functions as the gate through which the pulses to be counted are passed to the counter and (2) has its conductivity controlled by gaseous conduction electron discharge elements one of which responds to the start pulse and the other of which responds to the stop pulse. This insures substantially instantaneous operation of the gate for the reason that such gaseous elements respond in a time of the order of 10^{-8} sec. and have a very low impedance after they begin to conduct, thus permitting discharge of the associated capacitors at an extremely rapid rate.

The principal object of the present invention is to provide an improved electronic switch and method of operation whereby an electrical circuit may be opened and closed without appreciable time delay. Important objects of the invention are the provision of an improved switching circuit for controlling the supply of pulses to a counter, and the provision of a switch having control elements which are substantially instantaneous in action.

The invention will be better understood from the following description considered in connection with the accompanying drawings and its scope is indicated by the appended claims.

Referring to the drawings:

Figure 1 is an explanatory diagram relating to the type of square wave produced by a trigger circuit of the multivibrator type.

Figure 2 is a wiring diagram of one modification of the invention.

Figure 3 is a wiring diagram of another modification of the invention, and

Figure 4 illustrates the use of the invention in connection with several stages of tubes adapted to shape the pulses to a form suitable for driving a counter.

As indicated by Figure 1, the square wave produced by a trigger circuit of the multivibrator type has at one of its ends a slope which extends over a time interval t during which the pulses to be counted may not be passed through the gate to the counter. It can be seen that in counting pulses of very high frequencies a number of pulses may fail to reach the counter. As the pulse counting time T is decreased, the error due to this slope is increased. When $T=t$, no count is registered by the counter. This difficulty is avoided by the switching device of Figure 2.

The switching device of Figure 2 includes a

triode 10, a gas tube 11 to the control grid 12 of which a start pulse 13 of positive polarity is applied, and a gas tube 14 to the control grid 15 of which a stop pulse 16 is applied. All three of these tubes are biased off so that they do not conduct current. The output of the triode is applied to the grid 21 of an inverting tube 22 and the inverted output is applied to the common anode terminal 23 of a trigger circuit 24-25.

The application of the positive start pulse 13 to the grid 12 causes the tube 11 to draw current thus making the grid 17 more positive due to the voltage drop across the resistor 18-19. As a result the pulses 20 to be counted are transmitted through the triode 10 to the grid 21 of the inverter tube 22 which is normally biased off but is made conductive in response to each of the positive pulses 20'. These pulses are inverted by the tube 22 and reach the first trigger circuit 24-25 of the counter in the form of the negative pulses 20''.

The application of the stop pulse 16 of positive polarity to the grid 15 causes the tube 14 to draw more current through a resistor 26 which is connected in the anode lead of the triode 10. As a result, the anode 27 of the tube 10 is made more negative by the voltage drop of the resistor 26 and the transmission of the pulses 20 through the triode 10 is interrupted.

It will be noted that the start pulse 13 and the stop pulse 16 both reach the common anode terminal 23 of the first trigger circuit 24-25 of the counter in the form of a positive pulse and therefore produce no effect on the counter for the reason that its trigger circuits change from one of their stable conditions to the other only in response to the application of a negative pulse to the terminal 23. The trigger circuit 24-25 will of course be followed by as many similar circuits as are required to register the highest count to be considered, the anode of the second triode 25 etc. of each trigger circuit being connected through a lead 28 to the common anode terminal of the next successive trigger circuit.

It is apparent that the tubes 11 and 14 respond to the start and stop pulses substantially instantaneously and that they continue to conduct current until their anode potential is interrupted. For resetting the switching device in a standby condition with the tubes 11 and 14 not conducting and with current in the right hand triodes of the trigger circuits of the counter, the reset switches 29 and 30 may be opened and closed. These two switches may be ganged together so that this resetting of the device is accomplished by a single operation.

In the modification of Figure 3, the triode 10 of Figure 1 is replaced by a tetrode 31 and the stop pulse 16 is applied through the tube 14 to the screen grid 32 of this pentode. This modification, like that of Figure 1, isolates the counter from the switching pulses so that only the pulses to be counted are registered on the counter. Thus in the case of Figure 3 (1) the start pulse is made of such magnitude as to raise the potential of the grid 33 of the tetrode a value just below cut-off potential so that the start pulse does not appear in the output of the tetrode, (2) the pulses to be counted are inverted by the tetrode and applied directly to the common anode terminal 23 of the trigger circuit 24-25 and (3) the stop pulse causes the tube 14 to draw current

through a resistor 34 thus making the grid 32 more negative, interrupting the current of the pentode 31 and producing at the terminal 23 a positive pulse which has no effect on the count registered in the counter.

The gaseous electron discharge devices 11 and 14 may be connected at various places along the amplifier stages by which the pulses are shaped to a form suitable to be registered by the counter as indicated by Figure 4. Thus the tube 11 may operate in response to a start pulse as in the modification of Figure 1 to control the input to the three shaping stages 35, 36 and 37, and the tube 14 may function likewise in response to a stop pulse to interrupt the transmission of the counted pulses through the stage 37.

What the invention provides is an electronic switch which is substantially instantaneous in action due to the rapid response of the gaseous electron discharge elements which function to open and close the gate through which the transmitting circuit is completed.

I claim as my invention:

A high speed switching device including means for applying an operating potential, first and second gaseous conduction devices each having anode, cathode and grid electrodes, an electron discharge tube having anode, cathode and grid electrodes, a tapped resistor connected to the cathode of said first device, the grid of said electron discharge tube being connected to one of said resistor taps, a first anode load resistor connecting the anode of said first device with said operating potential applying means, a second anode load resistor connecting said second device anode and said electron discharge tube anode to said operating potential applying means, means for applying signals to said electron discharge tube grid, means for applying a start pulse to said first device grid to render it conductive whereby said electron discharge tube transmits said signals and means for applying a stop pulse to said second device grid to render it conductive whereby transmission by said electron discharge device is stopped.
